CATHODE RAY TUBE

Hans Werner Paehr, Berlin-Charlottenburg, Germany; vested in the Alien Property Custodian

Application January 26, 1940, Serial No. 315,635
In Germany February 9, 1939

5 Claims. (Cl. 250—162)

The invention relates to cathode ray tubes and in particular to the electron gun arranged within a cathode ray tube.

It is an object of the invention to provide a cathode ray tube having a cathode ray of small divergence and small cross section in the plane of the screen. It is a further object to utilize an electron gun producing such a ray in a tube having a comparatively large screen and a short distance between the cathode and the screen so that a wide angle of deflection must be used to scan the entire screen surface.

It is a further object to improve the electron gun systems hitherto in use with respect to control sensitivity and sharpness of the spot. Other objects of the invention will be apparent from the following description in connection with the drawing representing in

Fig. 1 a longitudinal section through the neck portion of the cathode ray tube and in

Fig. 2 a side view of a complete tube.

The most simple and in first approximation also true explanation of the electron optical arrangement of a cathode ray tube is that the emitting surface of the cathode is reproduced upon the screen of the tube by means of an electron lens. It has however been ascertained that the sharpest spot is obtained not as an image of the cathode surface but as an image of a cross section of the cathode ray immediately in front of the cathode at a point where the cathode ray has its smallest diameter. This cross section is usually called the cross-over point.

Up to the present time the development of electron gun systems has been in the direction to increase as far as possible the ratio between the emitting area of the cathode and the area of the cross section of the cathode ray in the cross-over point in order to reduce the specific emission load of the cathode surface and to obtain in spite thereof a high intensity in the cathode ray. This development was in the direction to large angles of divergency.

According to the invention it has been found that it is not preferable to use a ray with a large angle of divergency but that it is better to use a cathode ray with a divergency as small as possible.

The invention is of particular importance for television receiving tubes with intensity control by means of a variation of the potential of a Wehnelt cylinder and furthermore in connection with tubes having a large angle of deflection of 45° and more towards each side from the axis of the tube. Such tubes have been suggested in order

to obtain a short total length of the tube. Tubes of this type make use of inhomogeneous deflecting fields in order to obtain the necessary deflection upon a screen with a large radius of curvature. The consequence is that the luminescent spot is not sharply focused near the edges of the screen. It has however been found that this drawback can be overcome if a very narrow cathode ray is used having a divergency which is so small that the inhomogeneity of the deflecting field can be neglected within the space between the boundaries of the cathode ray.

Experiments about the requirements for the construction of a suitable electron gun have shown that an improvement of the directional effect can be obtained by increasing the ratio between the cut off voltage at the Wehnelt cylinder and the anode voltage. An increase of this ratio results however in a loss of control sensitivity. The invention points a way to improve the directional effect and to obtain a cathode ray bundle of small divergency without a simultaneous loss of control sensitivity.

According to the invention the Wehnelt cylinder includes a front portion which has at least partly the form of a cone or funnel opening towards the anode of the tube. It has been found that the inclination of the sides of the cone is very essential for obtaining the desired effect. According to the invention the opening of the cone has an angle of approximately 120°.

In Figs. 1 and 2 the cathode ray tube 6 has a neck portion 1 of cylindrical cross section. The neck portion has a foot 7 supporting a cathode 2 and a Wehnelt cylinder 3. The cathode is of the hairpin type carrying a small ball at the point of the bend. The Wehnelt cylinder consists of a cylindrical portion surrounding the cathode and a conical portion immediately in front of the cathode. The conical portion has a central aperture and opens towards the screen of the tube. The anode 4 has the form of a wall coating ending shortly before the Wehnelt cylinder. The concentrating fields is produced by a coil 5 on the outside of the neck of the tube. The deflecting systems are not represented in the drawing.

A system as described in connection with Fig. 1 produces a cathode ray of unexpected small divergency and has the advantage that the divergency remains practically constant when the current is increased while hitherto an increase of the current has always resulted in an increase of the angle of divergency. The gun system of the invention produces therefore a spot of more uniform diameter in intensity controlled tubes.

The experiments have shown that an angle of the cone of 90° and less, or of 160° and more has given much less favourable results.

The opening within the Wehnelt cylinder shall be as small as possible; a diameter of 1 mm. will however be the lower limit for practical reasons. The height of the cone in the direction of the tube axis shall be at least three or better four times as large as the diameter of the small aperture of the Wehnelt cylinder. Instead of a conical wall portion it is possible to use a heavy plate having a conical depression on the side towards the anode. The Wehnelt cylinder shown in the drawing is produced, for example, by pressing or stamping.

It is particularly preferable to use this form of Wehnelt cylinder in combination with a cylindrical anode of large opening. This is contrary to usual systems in which the anode has the form of a flat disc with a small aperture. The inner diameter of the anode cylinder shall be at least larger than the outer diameter of the Wehnelt or control electrode.

What I claim is:

1. A cathode-ray device adapted to provide an angle of ray deflection of the order of 45° or higher comprising a cathode, a conical control electrode apertured at its apex and positioned with said apex adjacent said cathode, and an anode comprising a hollow cylinder adjacent said conical electrode and unobstructed therefrom, the diameter of said cylindrical anode being greater than the outer diameter of said conical electrode whereby to provide a cathode ray bundle of small divergency without simultaneous loss of control sensitivity. 25

2. A cathode-ray device adapted to provide an angle of ray deflection of the order of 45° or higher comprising a cathode, a control electrode having a cylindrical portion surrounding said cathode and a conical portion apertured at its apex and positioned with said apex adjacent said cathode, and an anode comprising a hollow cylinder adjacent said conical electrode and un- 30

obstructed therefrom, the diameter of said cylinder being greater than the outer diameter of said conical electrode whereby to provide a cathode ray bundle of small divergency without simultaneous loss of control sensitivity.

3. A cathode-ray device adapted to provide an angle of ray deflection of the order of 45° or higher comprising a cathode, a conical control electrode having an apex angle between 90° and 160° and being apertured at its apex and positioned with said apex adjacent said cathode, and an anode comprising an unobstructed hollow cylinder, the diameter of said cylindrical anode being greater than the outer diameter of said conical electrode whereby to provide a cathode ray bundle of small divergency without simultaneous loss of control sensitivity. 10

4. A cathode-ray device adapted to provide an angle of ray deflection of the order of 45° or higher comprising a cathode, a conical control electrode having an apex angle of approximately 120° and being apertured at its apex and positioned with said apex adjacent said cathode, and an anode comprising an unobstructed hollow cylinder, the diameter of said cylindrical anode being greater than the outer diameter of said conical electrode whereby to provide a cathode ray bundle of small divergency without simultaneous loss of control sensitivity. 20

5. A cathode-ray device adapted to provide an angle of ray deflection of the order of 45° or higher comprising a cathode, a conical control electrode having an apex angle of approximately 120° and being apertured at its apex and positioned with said apex adjacent said cathode, the depth of said conical electrode being at least three times the diameter of the aperture of said conical electrode, and an anode comprising an unobstructed hollow cylinder, the diameter of said cylindrical anode being greater than the outer diameter of said conical electrode whereby to provide a cathode ray bundle of small divergency without simultaneous loss of control sensitivity. 30
